United States Patent Office.

GARRETTSON SMITH AND HENRY BROWN, OF PHILADELPHIA, PENNSYLVANIA, ASSIGNORS TO WILLIAM L. McDOWELL, OF SAME PLACE.

Design No. 3,426, dated March 23, 1869, antedated Feb. 23, 1869.

DESIGN FOR THE PLATES OF A COOK'S STOVE.

The Schedule referred to in these Letters Patent and making part of the same.

To all whom it may concern:

Be it known that we, GARRETTSON SMITH and HENRY BROWN, of the city of Philadelphia, in the State of Pennsylvania, have invented or produced a new and original Design for the Plates of a Cook's Stove, which we name "Umpire Cook," of which the following is a full, clear, and exact description, reference being had to the accompanying drawing, making a part of this specification, and to the letters of reference marked thereon.

Our design relates to the front and side plates of a cook's stove, and consists of the bas-relief panels a a of the side plate A, the bas-relief ornamented panels b c, and the ornamented relief panel d of the front plate B, as shown in the drawing.

What we claim as our invention, and desire to secure by Letters Patent, is—

The ornamental design for the plates of a cook's stove, herein set forth and shown.

GARRETTSON SMITH.
HENRY BROWN.
